TUFTING ATTACHMENT FOR SEWING MACHINES

Leonard L. Crouch, East Gastonia, N. C.

Application October 9, 1936, Serial No. 104,772

1 Claim. (Cl. 112—79)

My invention relates to an improved tufting attachment for sewing machines, and has for its object to provide a device that is simple in construction and efficient in operation and which is adapted to co-act with the stitching mechanism of an ordinary sewing machine for the purpose of producing tufted articles.

The invention consists of the novel construction and arrangement of the parts and combination of parts hereinafter more fully set forth in the following specification and pointed out in detail in the appended claim.

In the accompanying drawings:

Figure 1 is a front end elevation of a sewing machine having my invention applied thereto.

Figure 2 is a side elevation of the same.

Figure 3 is an enlarged detail elevation, partly in section, of my improved attachment.

Figure 4 is an enlarged detail side view of the looper and cutting blade.

Referring to the accompanying drawings, forming part of this specification, and in which like reference numerals designate like parts throughout the several views thereof, I designates a sewing machine of any well-known type and having a head 2, the said machine 1 being secured on a base 3. The head 2 is provided with the usual reciprocating needle bar 4, in which is carried the needle 5, having the usual eye for receiving the tufting thread 6. The tufting thread 6 is fed from a spool and any suitable form of tension may be employed in connection with the tufting thread. The sewing machine employs the usual means to reciprocate the needle, also the usual pressure foot 7 carried by a reciprocating pressure bar 8 which can be raised by the finger lever 9. The sewing machine also employs a work feeding means to advance the work from the operator including the dogs 10 operated through an opening in the base 3, said dogs are rigidly mounted upon the dog support bar 11. At one end the bar 11 is connected to the link, pivoted to the crank 12 which in turn is rigidly secured to the rock shaft 13. At its opposite end the bar 11 is provided with a fork 14 for the reception of a roller 15 pivotally mounted at 16 upon the crank 17 which in turn is rigidly mounted upon a rock shaft 18. It might be stated at this point that the movement of the rock shaft 18 serves to move the dog carrying bar 11 longitudinally while the movement of the rock shaft 18 serves to raise and lower the same. The foregoing description is that of an ordinary sewing machine such as now in general use.

The attachment comprises a bracket 19 which

is rigidly clamped to the lug 20, integral with the base 3, by means of the bolt 21, and is provided with a forked lower end 22. In the forked end 22 of the bracket 19 is adjustably secured a hub 23 which is held in the adjusted position by the bolt 24 and lock nut 25. The rock arm 26 is mounted on the hub 23 and has its upper end connected to the projection 27 of the bar 11 and is rocked back and forth by the action of said bar 11. The upper end of the rock arm 26 is provided with a laterally projecting looper 28, the lower edge of which is sharpened to form a cutting edge. The arm 29 is secured to the hub 23 by the bolt 30 and is prevented from turning on the hub by the pin 40 which projects through the said arm and into the hub 23. A cutting blade 31 has its lower end pivoted to the upper end of the arm 29 at 32 and its upper end is provided with an aperture 33 in which the ball 34 projects and upon which the cutting blade is fulcrumed. The said ball 34 also projects into the aperture 35 in the looper 28. The cutting blade is held tightly against the looper 28 by means of the spring 36. Between the spring 36 and the cutting blade 31 is a washer 37 having an aperture 38 into which the projection 39 of the spring 36 extends which holds the said washer securely in position against the cutting blade and forms a bearing surface for said cutting blade. When the bar 11 operates to move the goods being tufted along the machine it causes the arm 26 to rock and move the looper back and forth, at the same time operating the cutting blade to cut the loops as the goods advances. When the needle descends the looper moves out toward the needle and as the needle starts to raise it leaves a slight loop through which the looper projects and as the goods move forward the looper moves back and forth catching each loop as the needle starts to move up, leaving some of the loops on the looper as shown in Figure 4 and each time the arm 26 is rocked it cuts one of the loops as the looper starts to move forward. The arm 29 being stationary on the hub 23 the blade moves up and down each time the arm 26 is moved back and forth.

It will thus be seen that by using the ball 34 as a fulcrum point with the cutting blade, instead of a pivot, there will be practically no wear and the blade will always remain accurate.

Having thus described my invention, what I claim is:

In a tufting machine comprising a stitching mechanism including a reciprocating needle to carry the tufting thread through the fabric and

form loops thereunder, a work feeding bar having a projection on one end, a bracket secured to the under side of the machine, a hub rigidly secured to the lower end of said bracket and adjustable thereon, a rock arm mounted on said hub and adapted to be rocked by the projection on the work feed bar, a looper secured at one end to the upper end of the rock bar and having a cutting edge and an aperture extending therethrough, an arm having one end rigidly secured to the said hub, a cutting blade pivoted at its lower end to the upper end of said arm and hav-

ing an aperture in its side in line with the aperture in said looper, a ball fitted in the apertures of the blade and looper upon which the cutting blade operates, a washer having an aperture therethrough in line with the aperture in the cutting blade, and a spring secured at one end to the rock arm and having a projection at its upper end extending into the aperture in said washer and exerting its pressure against the same to hold the cutting blade securely in position.

LEONARD L. CROUCH.
